(57) **CLAIM**

The ornamental design for a water ride, as shown and described.

DESCRIPTION

FIG. 1 is a perspective view of a water ride showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing on the water ride is included for the purpose of illustrating unclaimed subject matter and forms no part of the claimed design. The dot-dash lines define the boundary of the claimed design and forms no part of the claimed design.
